UNITED STATES PATENT OFFICE.

ARCHIBALD PICKEN, OF ROANOKE, VIRGINIA.

MACHINE FOR GRANULATING TOBACCO.

SPECIFICATION forming part of Letters Patent No. 634,476, dated October 10, 1899.

Application filed February 17, 1898. Serial No. 670,650. (No model.)

To all whom it may concern:

Be it known that I, ARCHIBALD PICKEN, residing at Roanoke, in the county of Roanoke and State of Virginia, have invented a new and useful Improvement in Machines for Granulating Tobacco, of which the following is a full, clear, and exact description.

My invention is an improved machine for granulating tobacco, and has for its object, among others, to provide means for accurately granulating the tobacco-leaves, for feeding such leaves to the granulating devices, and for gaging the cut by means of devices connected with the cutting devices; and the invention consists in certain novel constructions and combinations of parts, as will be hereinafter described, and pointed out in the claims.

In the drawings, Figure 1 is a perspective view of my improved machine. Fig. 2 is a longitudinal section thereof. Fig. 3 is a detail enlarged section in the region of the cutters. Fig. 4 is a similar view showing a different position of the cutter-head. Fig. 5 is a side view of the feeding devices. Fig. 6 is a top plan view thereof. Fig. 7 is a sectional perspective view of the cutter-head from the rear side. Fig. 8 is a similar view from the front side. Fig. 9 is a perspective view of the base-cutter. Fig. 10 is a detail view of one of the spacing blocks or plates. Fig. 11 shows one form of transverse cutter, and Figs. 12, 13, and 14 illustrate a construction of transverse and upright cutters which I will presently describe.

In carrying out my invention I provide a suitable frame, which may consist, as shown, of side plates A on opposite sides of the infeed-belts B and C and supported at the front end of the machine by the legs D and at the rear or discharge end of the machine by the legs E, which have the guideways F for the cutter-head G, and bearings F' for the shaft H, which is provided with the eccentrics I for driving the cutter-head and with the cam J for operating the feeding devices, so the tobacco to be cut may be given a proper feed relatively to the cutting devices, as will more fully appear hereinafter.

The belts B and C move on their adjacent runs toward the cutter-head, as indicated by the arrows, and feed the tobacco gradually to

the cutting devices. It is preferred to make the lower belt longer than the upper one, so a portion of it will be exposed at the front 55 end of the machine to serve as a table to receive the tobacco to be granulated, which is then taken and conveyed by the belts B and C to the granulating devices. These belts are supported on suitable wheels or rollers 60 and are driven intermittently, so the tobacco will not be fed during the cutting operation, but only while the knives are clear of the feedway. This is accomplished by providing on the shafts B' and C' of the belts B and C 65 ratchet-wheels B² and C², which are engaged by the pawls B³ and C³ on a slide-bar J', which is moved longitudinally by the cam J on the shaft H, such slide-bar J' being guided by the studs J², operating in a longitudinal 70 slot J³, as shown in Fig. 5. By this construction it will be seen the belts B and C are operated on the return movement of the cutter-head to feed the tobacco forward one step. At the discharge end of the belt B, I support 75 in the casing the base-cutter K, which extends transversely and has its edge K' provided with the vertical slots K², which correspond to and receive the upright cutters of the cutter-head in the operation of the machine.

The cutter-head G is connected by the pitmen G' with the eccentric I on the shaft H, so it will be reciprocated as the shaft H is turned. I provide in this cutter-head a transverse cutter L and the vertical cutters M, the latter being preferably stepped and arranged to operate in the slots K² on the base-cutter, and in slots X in the top transverse bar X' of the feedway. (See Fig. 4.) This is important as it confines the tobacco in the feedway allowing it to escape in no way until cut off by the cutters, and also to be used as an edge with slots the same as K, K', and K² when the cutters shown in Figs. 12, 13, and 14 are used 95 in the upward cut.

In the construction shown in Figs. 2, 3, 4, 7, and 8 the upright cutters M are spaced apart, being preferably so held by spacing blocks or plates N, (shown in detail in Fig. 10,) and the blocks N and cutters M are formed to fit the undercut seats G² and G³ of the cutter-head, so such cutters and blocks may be slipped into the cutter-head from one end and

held by suitably applying and securing the end plate of the cutter-head; but the cutter may be held otherwise when desired.

It will be understood that the transverse cutter may be made with a straight edge, as shown in Fig. 8, or, when desired, in the shearing form shown at L' in Fig. 11, the cutter in the latter instance being made in sections and adapted to operate with a shearing action. It will also be understood that the transverse and upright cutters may be made, when desired, as shown in Figs. 12, 13, and 14, in which construction the upright cutters M' are formed with an enlarged shank M² and the transverse cutter L² is two-edged and is provided with slots L³, through which the upright cutters are passed, so they will be held by their shanks M² fitting in the slots L³, the upright cutter portions extending in advance of the transverse cutter, as best shown in Fig. 14. By this construction the transverse cutter operates to cut in both directions and to hold the upright cutters in position without the intervention of any separate 25 filling or spacing blocks. The upright cutters are not to be limited to an edge stepped into three cuts, but may be made in other shapes if desired; but the stepped construction is important, as the purpose in having 30 the cutter-blade stepped is twofold. First, with three successive cuts, the first step making its cut, say, one-sixteenth of an inch, the second step, coming after, cutting one-sixteenth of an inch deeper, and the third step, 35 coming still later, cutting another sixteenth of an inch, completing the cut. Thus are secured three cuts virtually with the same stroke of the blade at one motion, and it requires less 40 power, just as with three strokes you can more easily cut a stick in two than with one stroke. The second purpose in having the cutter stepped is to avoid disarranging the position of the tobacco, as is done in other machines 45 where the whole cut is made at once by one blade. The whole cut of the blade is made in three parts, each step cutting a third of the whole cut and at the same time only using the one blade and one motion. The desired 50 size of the cut, one-eighth of an inch, being so small and the nature of the leaf making it so easy to disarrange its position makes it necessary to use the best method, and from experiments it is found that a blade stepped 55 as shown gives the best results.

By the above term "disarranging" I mean that if the tobacco remains steadily in its position while being cut by the transverse cutter and the upright cutters, the size and shape 60 of the particles are uniform and of desired shape and size; but if it is disarranged by the passage of the cutters that uniformity is destroyed and the object of the machine frustrated. Therefore the cutters best adapted 65 to retain this steadiness are of great importance and the success of the machine depends greatly upon the same.

It will be noticed that the upright cutters extend in advance of the transverse cutter and operate as the cutter-head descends to 70 slit the tobacco longitudinally in advance of the transverse cutter. By this construction as the cutter-head descends the transverse cutter cuts off transversely the portions of the tobacco which have been slit by the 75 previous operation of the cutter-head, thus securing a granulation of the tobacco as desired.

In the cutter-head below the cutters I support a gage-plate O, which may be adjusted 80 toward and from the mouth of the machine or toward and from the base-cutter K to vary the size of the cut. In adjusting this gage-plate O, I may employ the brackets O', secured to the gage-plate and overlapping the 85 rear end of the bar O², on which such gage-plate is secured, and held to said bar O² by screws or bolts O³. By fitting one or more filling-blocks O⁴ between the bracket O' and the bar O² I am able to adjust the gage-plate 90 as desired.

In the operation of my construction motion is suitably given to the shaft H, which operates the cutter-head and also the feeding devices before described. As the cutter-head descends its transverse cutter will first reach the base-plate, as shown in Fig. 3, and will cut off a short length of the tobacco which has been fed between the belts B and C. As the cutter-head further descends the upright 100 cutters will pass through the tobacco in front of the transverse cut, such upright cutters passing into the slots K² of the base-cutter, thus slitting the tobacco which is fed by the belts B and C. As the cutter-head ascends 105 it will reach the position shown in Fig. 2, bringing the gage-plate opposite the space between the belts B and C, as shown in Fig. 2, where it will operate to limit the feed of the tobacco by the belts B and C. It is at this 110 position that the advance step is made in the feed motion, the feed operating only while the knives are clear of the throat of the feedway and the gage directly in the front of same and not during the return stroke of the 115 cutting-head and slide J', as stated, the cam J completing the action while the knives are clear of the feedway.

The bar X' above the throat of the feedway acts as a base against which to cut when the 120 double-edged knife shown in Figs. 12, 13, and 14 is employed.

Having thus described my invention, what I claim, and desire to secure by Letters Patent, is—

125

1. In a machine for granulating tobacco, a reciprocating cutter-head comprising a frame or carrier, blades or cutters secured thereto and having their cutting edges stepped, each step projecting in advance of the preceding one, and the transverse cutter carried by said head substantially as set forth.

2. In a machine for granulating tobacco, the combination of the framing having a feed-

way provided with bars above and below the same, said bars having slots, and the cutter-head reciprocating across said feedway and having upright cutters operating in the slots 5 of the upper feedway-bar and of the base bar or cutter substantially as set forth.

3. In a machine for granulating tobacco, a cutter-head comprising a frame having the opposite undercut seats, the cutters having at 10 their ends portions to fit in said seats, and the filling-plates interposed between the cutters and having at their ends portions fitting in the undercut seats of the frame and the transverse cutter carried by said head, substantially as set forth.

4. In a machine for granulating tobacco, the combination of the frame having a feedway, the reciprocating cutter having the upright and transverse cutters and provided with the 20 guard or stop plate arranged out of line with said cutters whereby it will face the feedway when the cutters are out of operative position, the base-cutter and one side of the feedway being provided with slots receiving the 25 upright cutters and means whereby the tobacco may be fed, substantially as set forth.

5. A machine for granulating tobacco comprising the framing, the base-cutter and upper transverse feedway-bar provided with 30 slots and the cutter-head having a transverse cutter and provided with upright cutters projected in advance of the transverse cutter and arranged to operate in the slots of the base-cutter and in the slots of the upper 35 transverse bar of the feedway, substantially as set forth.

6. In a machine for granulating tobacco, the combination of the framing, the infeed-belts, the base-cutter having slots spaced apart, the 40 cutter-head having transverse and upright cutters, the latter being arranged to operate in the slots of the base-cutter and upper transverse bar of the feedway, a gage-plate carried by the cutter and intermediate operating devices between the cutter-head and the feedbelts, whereby the feed-belts will be operated, 45 substantially as set forth.

7. In a machine for granulating tobacco, the combination of the framing, the reciprocating cutter-head, the feed-belts, the slide-bar for 50 operating said belts, and the shaft having a cam for operating the slide-bar and provided with eccentrics by which to reciprocate the cutter-head, substantially as set forth.

8. The machine for granulating tobacco, 55 consisting of the framing, the base-cutter having upright slots, the upper feedway-bar having slots, the reciprocating cutter-head having a transverse cutter, and provided with the upright cutters projecting in advance of 60 the transverse cutter and arranged to operate in the slots of the base-cutter, and in the slots of the upper feedway-bar, the feed-belt provided with the ratchet-wheels, the longitudinally-movable slide-bar having pawls en- 65 gaging the said ratchet-wheels, and the shaft having a cam by which to operate the slide-bar and provided with eccentrics connected with and adapted to operate the cutter-head, substantially as set forth.

9. A machine for granulating tobacco comprising a framing, the cutting devices, the feed mechanism including the opposite reversely-movable ratchet-wheels, the slide-bar 75 extended adjacent to said ratchet-wheels and having pawls engaging the same and adapted to operate the ratchet-wheels, and the shaft for operating said slide-bar, substantially as set forth.

10. A machine for granulating tobacco comprising the frame having a feedway and provided at one side of same with a base-cutter provided with slots, and a cutter-head reciprocating back and forth across said feedway and provided with upright cutters spaced 85 apart and having their cutting edges stepped and with a transverse cutter, such upright cutters being arranged to operate in the slots of the base-cutter substantially as set forth.
